UNITED STATES PATENT OFFICE

WILSON R. MYERS, OF NEW YORK, N. Y., ASSIGNOR TO ICE CREAM SMACK CORPORATION, OF NEW YORK, N. Y., A CORPORATION OF DELAWARE

CRIMPING MECHANISM FOR CYLINDER-FORMING MACHINES

Application filed May 22, 1928. Serial No. 279,753.

My invention relates to certain new and useful improvements in cylinder forming machines of the kind disclosed in the application of myself and Bernhard O. Opitz, Serial 5 No. 171,792. In that application is disclosed a machine consisting, generally, of a suitable frame on which is mounted a rotatable mandrel, a roll-of-paper holder, and mechanism for delivering paper from the roll to 10 the mandrel and severing the paper transversely into lengths; means are also provided for turning over or crimping a projecting end of the cylinder formed by the mandrel and pressing the crimped portion inwardly to 15 form a bottom for the cylinder. The crimper of that machine comprises a pivoted arm which, at proper intervals, presses down onto the projecting paper beyond the end of the mandrel to effect the crimping operation.

20 The crimper is moved to the crimper position by a cam on a reciprocating bar as the bar moves upwardly and is turned to its inactive position by spring action.

25 My present invention provides certain improvements whereby the crimper will be more effective in its action and will work equally as well when paraffined paper is used as when plain paper is employed.

30 When paraffine coated paper is used in the machine of the application aforesaid difficulty has been experienced with the paraffine coating the crimper arm and sometimes interfering with its efficient operation. Therefore, it is a primary object of my present invention to overcome this objectionable feature.

35 In order to carry out my invention I provide the crimper arm with an opening designed normally to lie in alignment with the 40 end of the mandrel, spring means being provided to bring the arm through the crimping position as well as to hold it in the normal position against a cam of a reciprocating rod which controls the operation of the crimper, 45 the cam being effective to hold the crimper in the normal position when the rod is down and to permit the spring to operate as the rod moves upwardly.

50 Another object is to provide the crimping arm with means to maintain its temperature

sufficiently high to melt any paraffine that may tend to accumulate on it.

A further object is to provide a crimper arm with a guide finger to ensure the proper directing of the paper, which forms the end of the cylinder, into the crimper, and to provide the lower portion of the crimper with a slot to permit the point of the bottom of the cylinder to pass through without unspinning the same. 55

60 Other objects will in part be obvious and in part be pointed out hereinafter.

To the attainment of the aforesaid objects and ends, my invention consists in the novel 65 details of construction and in the combination, connection and arrangement of parts, hereinafter more fully described and then pointed out in the claims.

In the drawings:

70 Figure 1 is a side elevation of so much of the cylinder forming machine as is necessary to illustrate the application of my invention.

75 Figure 2 is an enlarged detail side elevation of the final paper-feed rolls, the mandrel, the crimper, and the crimper-operation controlling bar, the same being in the normal or at rest position.

80 Figure 3 is a view similar to Figure 2 with the crimper-operation controlling bar elevated, and the crimper finger raised up after having passed the end of the mandrel and performed its crimping operation so as to be 85 out of the way when the presser member (not shown) moves into position.

85 Figure 4 is a detail perspective view showing the invention, the paper cylinder being shown in dotted lines.

90 In the drawing, in which like numerals of reference indicate like parts in all the figures, 1 is the frame of the machine, 2 one of the main rotating shafts, 3 the final paper-feed rolls, 4 the mandrel and 5 the reciprocating bar which controls the action of the crimper 95 and of the end presser member (not shown).

95 In the present embodiment of my invention the bar 5 is provided with a holding cam 6 that is adapted to engage, at its lowermost position, a roller 17 on the vertical arm 18 of 100

the crimper 8 which is pivoted at 7 to a suitable support.

The crimper 8 has an opening 9 of sufficient area to receive the paper cylinder on the mandrel as it is formed and this opening is normally held in alignment with the mandrel by engagement of the roller 17 with the cam 6, see Figure 2.

10 is the crimping finger which is adapted, on its upward movement, to engage the paper cylinder near its edge and press it inwardly toward the axis of the cylinder to effect the crimping or turning over of the paper on the mandrel to start the bottom-forming operation.

11 is the operating lever that effects reciprocation of the bar 5, the lever 11 being operated by a suitable cam 13 on the shaft 2 of the machine.

20 The lever 11 is connected to the bar 5 by a link connection 12 as in the machine hereinbefore referred to.

An extension 19, movable as one with the arm 8, has secured thereto a spring 14 that 25 functions to keep the roller 17 in engagement with the cam 6 or bar 5 according to the position of the cam and bar and this spring opposes the action of the cam 6.

30 The crimper finger 10 has a slot 20 that will permit free passage of the point α of the paper cylinder X so as not to unspin the same as the finger 10 moves upwardly beyond the axial line of the cylinder.

Furthermore, the arm 8 has an upper guide finger 21 whose under surface 22 extends tangentially to the curved surface 23 of the finger 10 and functions to guide the paper strip in its passage to and around the cavity of the crimper.

40 In order to maintain the temperature of the crimper arm 8 I provide a suitable electric heater 16 mounted on that arm or adjacent thereto so as to warm the metal of the arm and prevent the paraffine from piling up by adhesion thereto.

45 It will be seen that when the cam 13 presses down on the lever 11 it will elevate the bar 5. This action results in the spring 14 rocking the lever 19 so as to move the finger 10 upwardly. During this upward movement of the finger 10 the end of the paper cylinder (see Fig. 4) which lies in the concavity of the opening 9 is pressed upwardly. The cylinder being under rapid rotation the projecting 50 end of the cylinder is thus bent toward the axis and twisted as it were to partially close the bottom of the cylinder. As soon as the finger 10 has cleared the cylinder the crimping pressure member 5^a is swung up from the 55 position shown in Figures 1 and 2 to the position shown in Figure 4 to complete the formation of the bottom of the cylinder by pressing the crimped and infolded end tightly against the end of the mandrel. As the operation of the member 5^a is old in the prior

application above referred to and constitutes no part of the present invention detailed disclosure of its operating mechanism is thought to be unnecessary in this application.

In the operation of my present invention it will be noted that the crimping action takes place on the upward movement of the finger 10 instead of on the downward movement of the crimping arm as in the application aforesaid. By changing the direction of movement of the arm in this way I am enabled to employ the electric heater in a position where it will function to warm the arm and not over-heat the paraffine on the paper itself.

70 From the foregoing description, taken in connection with the accompanying drawing, it is thought that the complete construction, 75 operation and advantages of my invention will be clear to those skilled in the art to which it relates.

80 What I claim is:

1. In a machine of the character described, a rotatable mandrel, a pivoted crimper and a reciprocating crimper-operation controlling bar having a cam, said crimper having a portion engaging said cam, and a spring continuously tending to move said crimper in opposition to said bar, said crimper including an arm having a forked end provided with an opening aligning normally with said mandrel.

90 2. In a machine of the character described, a rotatable mandrel, a pivoted crimper and a reciprocating crimper-operation controlling bar having a cam, said crimper having a portion engaging said cam, and a spring continuously tending to move said crimper in opposition to said bar, and means to maintain the crimper heated for the purposes described.

100 3. In a machine of the character described, a rotatable mandrel, a pivoted crimper and a reciprocating crimper-operation controlling bar having a cam, said crimper having a portion engaging said cam, a spring continuously tending to move said crimper in opposition, to said bar, said crimper including an arm having a forked end provided with an opening aligning normally with said mandrel, and means to maintain the arm heated for the purposes described.

110 4. In a machine of the class described wherein is provided a rotatable mandrel, a crimper, a crimper operation-controlling bar and means to actuate said bar, said crimper comprising a bell crank lever, one end of which is forked to provide an opening to receive the formed cylinder, the other end of said lever having a roller, said bar being reciprocable and having a cam to engage said roller when the lever is down for the purpose of holding said opening in alignment with said mandrel.

120 5. In a machine of the class described wherein is provided a rotatable mandrel, a

5 crimper, a crimper operation-controlling bar and means to actuate said bar, said crimper comprising a bell crank lever, one end of which is forked to provide an opening to receive the formed cylinder, the other end of said lever having a roller, said bar being 70 reciprocal and having a cam to engage said roller when the lever is down for the purpose of holding said opening in alignment with said mandrel, and an electric heater associated with said lever, substantially as shown 75 and described.

10 6. In a machine of the character described, a rotatable mandrel, a pivoted crimper, a reciprocating crimper-operation controlling bar having a cam, said crimper having a portion 15 engaging said cam and a spring continuously tending to move said crimper in opposition to said bar, said crimper including an arm having a forked end provided with an opening aligning normally with said mandrel, said forked end comprising a lower finger having a curved working surface, and an upper finger having a working surface 20 approximately tangent to the curved surface. 25

7. In a machine of the character described, a rotatable mandrel, a pivoted crimper and a reciprocating crimper-operation controlling bar having a cam, said crimper having a portion 30 engaging said cam, and a spring continuously tending to move said crimper in opposition to said bar, said crimper including an arm with an upper finger and a lower finger, said lower finger having a transverse 35 slot for the purposes described.

40 8. In a machine of the character described, a rotatable mandrel a pivoted crimper and a reciprocating crimper-operation controlling bar having a cam, said crimper having a portion engaging said cam, and a spring continuously tending to move said crimper in opposition to said bar, said crimper including an arm with an upper finger and a lower finger, said lower finger having a transverse slot, 45 said upper finger having a straight paper guiding surface which merges with a curved surface at the junction of said fingers.

45 9. In a machine of the character described, a rotatable mandrel, a pivoted crimper and a reciprocating crimper-operation controlling bar having a cam, said crimper having a portion 50 engaging said cam, a spring continuously tending to move said crimper in opposition to said bar, said crimper including an arm having a forked end provided with an opening aligning normally with said mandrel, and means to maintain the crimper heated, said forked end comprising an upper finger and a lower finger, the combined working faces 55 of said fingers including a curved portion and a straight portion for the purposes specified.

60 10. In a machine of the class described wherein is provided a rotatable mandrel, a 65 crimper, a crimper operation-controlling bar

and means to actuate said bar, said crimper comprising a bell crank lever, one end of which is forked to provide an opening to receive the formed cylinder, the other end of said lever having a roller, said bar being reciprocal and having a cam to engage said roller when the lever is down for the purpose of holding said opening in alignment with said mandrel said forked end comprising a lower short curved finger and an upper long straight finger. 75

11. In a machine of the class described wherein is provided a rotatable mandrel, a crimper, a crimper operation-controlling bar and means to actuate said bar, said crimper comprising a bell crank lever, one end of which is forked to provide an opening to receive the formed cylinder, the other end of said lever having a roller, said bar being reciprocal and having a cam to engage said 80 roller when the lever is down for the purpose of holding said opening in alignment with said mandrel said forked end comprising a lower short curved finger and an upper long straight finger, said lower finger having 85 a slot for the purpose specified.

12. In a machine of the character described, a rotatable mandrel, a pivoted crimper and a reciprocating crimper-operation controlling bar having a cam, said crimper having a portion 90 engaging said cam, and a spring continuously tending to move said crimper in opposition to said bar, said crimper including an arm with an upper finger and a lower finger, said lower finger having a transverse slot, and means for heating said crimper. 100

13. In a machine of the character described, a rotatable mandrel, a pivoted crimper and a reciprocating crimper-operation controlling bar having a cam, said crimper having a portion 105 engaging said cam, and a spring continuously tending to move said crimper in opposition to said bar, said crimper including an arm with an upper finger and a lower finger, said lower finger having a transverse slot, 110 said upper finger having a straight paper guiding surface which merges with a curved surface at the junction of said fingers, and means for heating said crimper.

14. In a machine of the character described, a rotatable mandrel, a pivoted crimper, means for reciprocating said crimper, said crimper including an arm having a forked end providing a lower finger and an upper finger, the working face of said lower finger and a portion of the working face of said upper finger being curved and of a radius approximately that of the exterior of the cylinder to be formed, said upper finger including a straightway working surface portion merging with the curved surface and extending approximately tangentially thereto for the purpose specified. 115

15. In a machine of the character described, a rotatable mandrel, a pivoted crimper, means 120

for reciprocating said crimper, said crimper including an arm having a forked end providing a lower finger and an upper finger, the working face of said lower finger and a portion of the working face of said upper finger being curved and of a radius approximately that of the exterior of the cylinder to be formed, said upper finger including a straightway working surface portion merging with the curved surface and extending approximately tangentially thereto, an electric heating unit carried on said arm in association with the upper finger, for the purposes described.
